DESIGN FOR A PLAQUE

Frank Powell, Miami, Fla.

Application December 22, 1944, Serial No. 117,019

Term of patent 7 years

(Cl. D29—23)

To all whom it may concern:

Be it known that I, Frank Powell, a citizen of the United States of America, residing in Miami, county of Dade and State of Florida, have invented a new, original, and ornamental Design for a Plaque, of which the following is a specification, reference being had to the accompanying drawing, forming part thereof.

The figure on the drawing is a perspective view of a plaque showing my new design.

I claim:

The ornamental design for a plaque, substantially as shown.

FRANK POWELL.
